UNITED STATES PATENT OFFICE.

CHRISTOPHER WILMANNS, OF INDIANAPOLIS, INDIANA.

DESIGN FOR A SMOKER'S STAND.

Application filed August 4, 1927. Serial No. 22,995. Term of patent 7 years.

To all whom it may concern:

Be it known that I, CHRISTOPHER WILMANNS, a citizen of the United States, residing at Indianapolis, in the county of Marion and State of Indiana, have invented a new, original, and ornamental Design for a Smoker's Stand, of which the following is a specification, reference being had to the accompanying drawings, forming a part thereof.

In the drawings,—Figure 1 represents a side view of a smoker's stand showing my new design; Fig. 2 is a top plan of the upper portion of Fig. 1 showing the design on the top of the stand; and Fig. 3 is a plan view showing the design of the under or base portion of the stand.

I claim:

The ornamental design for a smoker's stand, as shown.

In testimony whereof, I affix my signature on the 30th day of July, 1927.

CHRISTOPHER WILMANNS.
